UNITED STATES PATENT OFFICE

ERNEST DUSCHER, OF LA CROSSE, WISCONSIN, ASSIGNOR TO THE VOTE BEGER COMPANY, A CORPORATION OF WISCONSIN.

TYPE-SETTER

1,043,910.

Specification of Letters Patent. Patented Nov. 12, 1912.

Application filed May 13, 1911. Serial No. 628,925.

To all whom it may concern:

Be it known that I, ERNEST DUSCHER, a citizen of the United States, residing at La Crosse, in the county of La Crosse and State 5 of Wisconsin, have invented a new and useful Improvement in Type-Setters, of which the following is a specification.

My invention relates to improvements in the art of setting and distributing type and 10 is distinguished from prior devices in this art by the use of a line unit case which operates with a font to receive and distribute type.

A further distinctive feature of this invention resides in the construction of type 15 employed whereby the mechanism for setting and distributing is adapted to support the type by engaging below shoulders thereon.

Through the use of the above features of distinction I have produced a device which is exceedingly simple and inexpensive in construction and effective in operation. By 20 its use an unskilled operator can easily and quickly set and distribute type, thus making the invention particularly valuable for office use in handling type in connection with office duplicating machines.

In the accompanying drawings forming 25 part of this specification, Figure 1 is a normal plan of my invention looking down as indicated by the line Y—Y, Fig. 2; Fig. 2 is a side elevation; Fig. 3 is an enlarged detail showing the parts of the line unit case carrier in normal position; Fig. 4 is a view 30 similar to Fig. 3 showing the parts of the carrier in position when a type is being released from the font and about to be conducted to the line unit case, a portion of said carrier being broken away and in section to more clearly illustrate the parts which directly coact with the type to release the latter; Fig. 5 is a front elevation of the line 35 unit case carrier without a line unit case, a portion of its guide shaft being shown; Fig. 40 6 is a plan of a detail of the font case and line unit case illustrating the mechanism by which the feed is caused to register accurately with any one of the type channels in 45 the font; Fig. 7 is a detail looking at an end of a portion of the font; Fig. 8 is an enlarged section taken on the line X—X of Fig. 3; Figs. 9 and 10 are side views of one

of the type employed in the use of my invention; Fig. 11 is a plan of a detail of the 55 font case showing the line unit case carrier applied thereto for distributing the type from a line unit case into said font, and Fig. 12 is an enlarged side elevation of a detail showing the line unit case carrier applied to 60 the font to distribute the type from a line unit case into said font, the parts of the feeder on said carrier being in a position illustrating one of the type as it is being admitted into a channel in the font, a portion 65 of said feeder being broken away to more clearly illustrate the feeding mechanism.

In the accompanying drawings A represents a font case in which type are adapted to be held and B is a line unit case carrier 70 which is adapted to coact with said case to set type therefrom in a line unit case C as illustrated in Figs. 1 to 4 inclusive, or to distribute type from said line unit case into said font as illustrated in Figs. 11 and 12. 75

Where the term "font" is employed in this specification and in the claims following, I mean it to include what is generally known as a "case" for holding a complete assortment of different kinds or sizes of 80 type.

Font.—The font or font case is supported longitudinally in inclined position upon a stand 2 or other suitable support and has a plurality of longitudinal type holding channels 3 of even width and depth throughout the length of the font case. The sides or ribs 4 of the channels have a line of upwardly projecting stops 5 disposed across the lower end of the case against which the 85 shoulders 6 on the type 7 catch, thus holding the type in longitudinal rows in the font so that as fast as a type in a row is mechanically removed from the type case the remaining type will feed by gravity toward 90 the delivery end 8 of said case.

Studs 9 are inserted at the lower ends of the channels below the stops 5 and their heads 10 likewise act as stops against which the shanks 11 of the type are adapted to 100 impinge. The height of the heads 10 above the lower ends of the shanks of the type corresponds with the height of the stops 5 above the lower edges of the shoulders of the type and all of the stops (including the 105 heads) adjacent to each channel are in

alinement at right angles across the channel. The type are arranged alphabetically in the channels, type of one character being allotted to each channel. Channels are also 5 provided for slugs and blanks which contribute toward making a complete font of type for commercial use.

The font of type is covered by a plate 12 of glass or other material secured to the 10 case by screws 13, strips of felt 14 being placed below the side edges of the plate and on the font case preventing the glass from cracking. The upper and lower edges of the plate are spaced from the receiving and 15 delivery ends 15 and 8 respectively of the font case for purposes hereinafter described.

The channels are properly indexed to correspond with the type by printing or marking across the plate and above the channels 20 near the end of the font. For this purpose thin bands 16 and 17 are painted or otherwise inscribed across the plate bearing the index inscriptions. The receiving and delivery ends of the font are provided with 25 guide shaft supports in the form of brackets 18 and 19, one pair being disposed at each end of said case and adapted to receive and detachably hold in a horizontal and transverse position parallel to the ends of the 30 frame, a shaft 20 which forms part of the type feeder B. Each bracket is slotted transversely at 21 to receive said shaft and a cotter pin 22 is inserted through the bracket across the slots and side of each end 35 of the shaft to fasten the shaft in place. The brackets are secured to the sides of the font by means of bolts 23 and are curved down below the inclined plane thereof.

Line unit case and type.—The line unit 40 case C in which type are adapted to be set and from which type are distributed consists of a pair of vertical sides 25 and 26 evenly spaced apart and formed with ends 27 and 28. The type such as 7 is set with 45 its shank 11 depending in the space between the sides with the opposite shoulders 6 resting on the upper edges 29 on said sides. The sides of the line unit case are of spring material so that they can be spread slightly 50 to permit the type being set therein and removed therefrom. After the line unit case is filled the type may be held or locked in the case in any ordinary manner such as by a set screw 30 and follower 31.

Type setting.—The line unit case carrier B which is adapted to select type from the font and set them in a line unit case, and to remove the type one at a time, from the line unit case and place them in the proper 60 channel in the font is in the form of a carriage 35 having two parallel sides 36 spaced evenly and sufficiently apart to receive freely an end of the line unit case C, said sides having upper parallel edges 37 sloping 65 down from the delivery end 8 of the font

to the top edges 29 of the line unit case so that type are adapted to slide by gravity from the font while hanging by their shoulders 6 on the edges of the sides 36 with their shanks guided down into the line unit case. The sides 36 of the carriage are integral with a floor 40 of the body 41 and said floor is formed with a stop shoulder 42 which is adapted to limit the insertion of the line unit case between the walls 36 of the carriage. The walls 36 are also formed with inner over-hanging shoulders 43 (see Fig. 8) flush with the inner walls of the line unit case when said walls are spread to allow the type to drop freely between them or be easily removed. The line unit case is held in the carriage and its walls are spread by means of a ball 44 playing in the opening 45 in the door 40 of the carriage and a spring leaf 46 secured to said carriage by the screw 47 with its free end pressing the ball upwardly between the lower chamfered edges 48 (see Fig. 8) of the sides 25 and 26 of the line unit case. The carriage 35 is mounted on a pair of sleeves 50 disposed on opposite sides thereof, said sleeves being journaled upon the bushing 51 which in turn is mounted upon a support 52 which is secured by screws 53 to the carriage. The entire end of the carriage is slidably secured to the body of the font by a gib rail 54 secured by bolts 55 and serving to assist in guiding the carriage as it slides on the shaft 20 and hold the inner end of the carriage in position longitudinally to register with the type channels in the font case. For the purpose of removing type from the channels in the font the carriage 35 is provided with a kick-off pin 60 working in a guide opening 61 in the carriage, the inner end of said pin being reduced in diameter and adapted to work in an opening 62 back of the stop pin 10 in the floor of the type channel with which the feeder registers, and push the lowermost type in the channel up and release it so that the type following will slip and eject it over the shoulders 5 and 10, thus causing it to slide down with its shoulders resting on the edges 37 of the sides 36 of the carriage.

The kick-off pin and presser plate 63 which carries guide pins 64 slides in the body 41 of the carriage. Coiled expansion springs 65 surrounding pins 64 serve to return the presser plate and retract the kick-off pin into normal position in readiness to repeat its operation of ejecting a type.

When in normal position as illustrated in Fig. 3, the kick-off pin does not enter the opening 62 in the floor of the type channel with which the carriage registers. A guard 66 in the form of an arm extends over the channel to allow only one type at a time to be kicked off. The arm is bifurcated at its lower end and its bifurcations are secured

to lugs 68 which are disposed on the opposite sides 36 of the carriage. The bifurcations 67 span the sides 36 of the carriage so that the type are free to slide down into 5 the line unit case on the edges 37 of said sides.

It will be noted that the arm 66 has an upwardly extending off-set portion 69 which allows the lower-most type or slug to be 10 pushed up and out of engagement with the stops adjacent the channels in which the type are held, while the portion 70 of said arm prevents the remaining adjacent type or slug in the channel from being disturbed. 15 The upper extremity of the guard 66 is shaped with an index pointer 71 extending over the index 16 on the plate 12 of the font case and serves to indicate the character of type with which the carriage registers. To 20 operate the kick-off pin 60 a pair of bell crank levers 72 each having two arms 73 and 74 is pivoted on the bushing 51. The work arms 73 are provided with an antifriction roller 75 suitably journaled on a bolt 76 and bearing against the presser plate 63. The 25 free end of the pair of work arms 74 of said lever is connected by pivots 77 working in slots 78 in the sides of a pair of operating levers 79 which are in turn pivoted between their ends by a pin 80 upon the outer end of a pair of swinging links 81. The free end of the pair of levers 79 is provided with a handle 82 by which motion is 30 imparted to the kick-off pin 60. The swinging levers 79 are pivotally mounted upon the links 81 and have their members disposed on each side of the carriage. By pushing the hand levers forward into the position 35 illustrated in Fig. 4 from the position illustrated in Fig. 3 the swinging links 81 are first moved forward and when resistance becomes great enough the arms 74 and 79 buckle and the work end of the arms 73 of the pair of bell crank levers moves up carrying with it the presser plate 63, thus depressing the springs 65, pushing the kick-off pin 60 up and causing the reduced end thereof to enter the opening 62 and impinge against the lower-most type in the channel until it 40 is raised and released from the channel over the shoulders 5 and 10. The kick off pin 60, handle 82, intermediate actuating mechanism and supports for said parts described for operating said pin constitute what I 45 term the type feeder.

In order to center the carriage so that it will register accurately with the channels in the font, a pair of centering pins 90 and 91 are slidably mounted in the lugs 68 and 69 50 on the sides 36 of the carriage 35. These pins are held in normal position out of engagement with the font as illustrated in Fig. 3 by means of coil springs 93. When the carriage has been moved until the index 55 pointer 71 coincides with the mark on the

index indicating the type which is desired to be released from the type font and set in the line unit case, the hand lever is pushed forward into the position indicated in Fig. 4 whereupon the centering pins being 70 so positioned as to impinge against the front edges of the swinging levers 81, the first impulse of said hand lever causes the swinging levers 81 to move forward carrying with them the pins 90 and causing the ends of 75 said pins adjacent the font to enter conical recesses 94 which are formed in the ends of the side walls 4 of the type channels in the font. The entering ends 95 of the pins 90 are conical and pressure upon the pins causes 80 the guide groove between the sides 36 of the line unit case carrier to register accurately with the channel of the font holding the desired type. Further movement of the hand lever thereupon causes the depression of the 85 kick-off pin which is permitted by the accurate registration of the carriage with the type channel to register with the opening 62. When the handle 82 is released the springs 65 and 93 return the feeder parts 90 to normal position and the springs 93 also withdraw the pins from the recesses 94. It will be noted that the conical shaped recesses as illustrated in Fig. 7 are disposed so that each depression centers in a type channel. 95

Type distributing.—When the line unit case carrier is used to distribute type from the line unit case into the font the carrier is adjusted to the receiving end 15 of the font by removing the shaft 20 from the pair of brackets 18 and attaching it in the recesses 21 in the pair of brackets 19, the cotter pins 22 which are used for holding the shaft in the brackets 18 being employed to prevent the shaft from being removed from the 100 brackets 19. The carriage 35 is assisted in being slidably held on the font case by means of the gib rail 95 as at the delivery end of the machine and in this manner the line unit case carrier is movable across the receiving 105 end of the font on the shaft 20 and the gib rail 95 and can be made to register the type groove in the carriage with the type holding channel in the font as desired.

The receiving end of the type font has the 110 sides or ribs of the type channels formed with conical indents 96 as at the delivery end of the font for the purpose of receiving the centering pins 90 and 91 and causing the channel in the type carrier to accurately 115 register with the desired channel in the font to properly conduct the type.

The index pointer 71 is adapted to indicate on the index 17 the relative position of the line unit case carrier on the font and the 120 operation of ejecting type from the line unit case carrier into the font is very similar to the operation when type are released from the font and set in the line unit case.

To distribute type from a line unit case 125

the latter is inserted in the carriage 35 as illustrated in Fig. 12 and the type slide from the line unit case on their shoulders upon the edges 37 of the sides 36 of the carriage 5 until the shoulders 6 on the lower-most type impinge against the stops 97 upon the upper edges 37 at the lower ends of the sides 36 and the lower end of the lowermost shank 11 impinges against the stop 98 at the lower-most end of the type channel formed by the sides 36. The stops 97 and 98 are of equal height and correspond in height with that of the shoulders 6 on the type. These stops 97 and 98 do not in any way impair the 10 successful operation of setting the type in the line unit case at the delivery end of the machine for in that position the type escape over these stops. The raised off-set portion 69 of the guard 66 permits free movement 15 of the type upon the shoulders while its main portion prevents more than one type at a time escaping. In order to release the lower-most type in the channel between the sides 36 of the type feeder an auxiliary kick-off pin 99 is provided which plays in an opening 100 immediately adjacent a corresponding opening 61 in which the kick-off pin 60 works. The kick-off pin 99 is similar in shape to the pin 60 and is similarly 20 attached to the presser plate 63. Its end 101 which is reduced in diameter is adapted to pass through an opening 102 in the line unit case carrier and impinges against the lower end of the shank 11 of the lower-most 25 type in the line unit case carrier and lifts the type from engagement with the stops 97 and 98 permitting it to slide over and into the channel of the font case with which the line unit case carrier registers. When 30 the kick-off pins 60 and 99 are in raised position as illustrated in Fig. 12 the pin 60 projects through the opening 103 in the floor of the channel of the type font and the lower end of the type which is released lodges 35 against the inner end of the pin 60 until the handle 82 is released into normal position. The lodging of the type on the pin 60 prevents more than one type entering 40 the channel in the font, if for any reason 45 more than one type is released from the line unit case carrier at a time. The pin 99 performs a similar function at the delivery end of the machine by preventing more than one type entering the line unit case at a 50 55 time and acting as a check to prevent mistakes being made by the operator.

The cover plate 12 has its upper and lower ends spaced from the receiving and delivery ends 15 and 8 of the font so that the guard 60 66 will closely coöperate with the surface of the font and the type to perform its functions as above stated.

Operation.—To set type a line unit case C is placed in the line unit case carrier B 65 as illustrated in Figs. 2 and 3. The handle

82 is grasped by hand and said carrier moved on the shaft 20 to register successively with the lower ends of the desired channels in the font A according to the index 16 with which the pointer 71 coincides. When the pointer coincides with an index mark indicating a type which it is desired to set in the line unit case the handle 82 is pressed forward into the position indicated in Fig. 4 and released. This operation is repeated until the line unit case is filled when it is removed and an empty case substituted. Each time the handle is pressed forward, the registering pins 90 and 91 enter a pair of recesses 94 thus causing the guide groove between the sides 36 of the line unit case carrier to accurately register with the desired type channel in the font so that a released type will slide down into the line unit case without catching. During the forward movement of the handle 82 and after the line unit case carrier B has registered the kick-off pin 60 which has also been made to accurately register with the opening 62 enters the lower portion of the type channel and raises the lower-most type in the channel out of engagement with the stops 6 and 10 and the released type thereupon slides upon its shoulders down the channel way in the line unit case carrier 95 and into the line case. The handle 82 is then released which completes an operation.

To distribute type the shaft 20 is detached from the brackets 18 by removing the pins 22 and adjusting the line unit case carrier B to the receiving end of the font. The ends of the shaft are seated in the recesses 21 of the brackets 19 and the pins 22 secured to said brackets while the body of the line unit case carrier engages on the gib rail 95. A line unit case carrying type to be distributed in the font is adjusted to the line unit case carrier as illustrated in Fig. 12, the type sliding down automatically upon their shoulders which are guided upon the edges 37 of the sides 36, the lower-most type ledging against the stops 97 and 98 in position to be ejected by the kick-off. The line unit case carrier is then moved across the upper end of the font and when the pointer 71 coincides with a mark on the index 17 corresponding with the character of the lower-most type in the line unit case carrier the handle 82 is pushed forward into the position shown in Fig. 12. This operation first actuates the registering mechanism causing the line unit case carrier to register its channel accurately between the sides 36 with the desired channel in the font. Complete movement of the handle 82 as in the operation of setting types actuates the kick-off mechanism and releases the lower-most type permitting it to travel down the desired channel in the font after the handle 120 125 130

82 is released. The guard 66 is of insufficient width to obscure the types in the lower end of the guide groove of the line unit case carrier leaving the type exposed to view. Should it be desired, the guard may be provided with a sight opening having a transparent magnifying closure over the lowermost type.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A type setter, comprising, a font for holding an assortment of shouldered type, a line unit case, a carrier for said case movable across said font having a guide for the type, said font, guide and case being adapted to support and suspend type by their shoulders, and means on said carrier for removing a type at a time from said font and setting it suspended by its shoulders in said case.

2. A type setter, comprising, a font for holding an assortment of type, a line unit case having expansible sides, a carrier movable transversely across said font with which said line unit case is separably connected, means on said carrier for spreading the sides of said case apart to receive type freely between them and means on said carrier for removing a type at a time from said font and setting it between the walls in said case.

3. A type setter, comprising, in combination, a font for holding an assortment of type, a type feeder movably mounted to travel across said font and a line unit case carried by said feeder into which type are adapted to be set having expansible sides, said feeder being provided with means for selecting type from said font, means for conducting selected type from said font to said case, means for causing said feeder to be held in engagement with said font while said means for conducting type registers with said font, and means for spreading the sides of said case to receive type freely.

4. A type font inclining longitudinally and having type channels in which shouldered type are adapted to be held in longitudinal rows and adapted to feed forward by gravity, a line unit case, a feeder adapted to be engaged with said font to hold said case longitudinally and conduct selected type by gravity from said font into said case, a kick-off on said feeder adapted to release a type from said font into said case and means for operating said kick-off, said

font, feeder and case being adapted to support and suspend type by their shoulders only.

5. A type setter, comprising, in combination, a type font inclined longitudinally and having type channels in which shouldered type are held in longitudinal rows and adapted to feed by gravity, a line unit case, a type feeder in which said line unit case is held and adapted to carry type from a channel in said font to said case, means for feeding a type from said font to the carrier leading into said case and a register co-operating with said font and feeder to align said feeder with a channel in said font, said font, feeder and case adapted to support and suspend type by their shoulders only.

6. In a machine having a type font with type channels and inwardly tapering depressions adjacent to said channels, a line unit case, a line unit case carrier, a feeder for setting type from said font into said case, the sides of said channels, line unit case and carrier being adapted to support and suspend shouldered type by their shoulders and a register having a tapering depre- 90 ssible pin adapted to enter one of said depressions and cause said feeder to register with a channel in said font.

7. In a machine having a type font with type channels, a line unit case, a line unit case carrier, a feeder adapted to move across said font, the sides of said channels, case and carrier being adapted to suspend shouldered type by their shoulders and a register 100 adapted to cause said feeder to coincide with a channel in said font and conduct type by their shoulders into a line unit case on said carrier.

8. In a machine for setting type, a font having type channels and tapering depressions adjacent to said channels, a line unit case and a type feeder movable across the channels in said font and serving to hold said case, said feeder having a tapering register adapted to co-operate with said font in said tapering depressions to cause said line unit case to register with the type channels therein automatically, said channels, case and feeder being adapted to suspend 110 shouldered type by their shoulders, a kick-off for releasing type from said font into said case and means for consecutively operating the register and the kick-off.

9. In a machine for setting type, a font having a plurality of type channels, a line unit case, a type feeder movable across the channels in said font and adapted to hold said case in position to receive type from said font, said channels, line unit case and feeder having sides adapted to support and suspend shouldered type by their shoulders, means for causing said feeder to register with any one of said channels in said font, means for releasing a type from the channel 130

- in said font with which said case registers and means controlled by the operation of said releasing means for operating said register automatically preceding the operation of said releasing device.
- 5 10. In a machine for setting type, a font having type channels, a line unit case, a type feeder movable across the channels in said font and having an automatically depressible alining element adapted to bring said case into exact alinement automatically with one of said channels at a time and allow type to pass from said font into said case, said feeder having a guide for said type and said channels, case and guide having sides adapted to suspend shouldered type by their shoulders, a pin movable in said carrier and adapted to engage and release a type from a channel in said font and means for operating said pin, said font, type guide and line unit case being inclined down in the same general direction to permit type moving by gravity on their shoulders from said font into said case.
- 15 20 25 30 35 40 45 50 55 60 65 70 75 80 85 90 95 100 105 110 115 120 125 130
11. In a machine for setting type, a longitudinally inclined font having channels serving to hold type in longitudinal rows and inwardly tapering depressions adjacent said channels, a line unit case, a carrier holding said case in longitudinal position movable across the lower ends of the channels in said font, a resilient alining element having a pointed end adapted to enter said depressions to bring said case into alinement successively with said channels, said carrier having a longitudinal guide adapted to direct type from one of said channels at a time into said case, and said channels, line unit case and carrier having sides adapted to suspend shouldered type by their shoulders, said font having openings below the lower-most type in said channels, a kick-off on said carrier adapted to pass through any of said openings, release a type from a channel in said font and permit said type to pass by gravity down said guide and into said line unit case on its shoulders, a hand operating lever adapted to actuate said kick-off and means for returning said lever and kick-off into normal position automatically.
12. In a machine for setting type, a longitudinally inclined font having channels to hold type in longitudinal rows, a line unit case having expansible sides, a carrier holding said case in longitudinal position movable across the lower ends of the channels in said font and adapted to bring said case into alinement with said channels, said carrier having means for spreading the sides of said case and a longitudinal guide inclining from said font to said case adapted to direct type from said channels into said case, said font having openings below the lower-most type in said channels, a kick-off on said carrier adapted to pass through an opening in the channel with which said guide connects and to release a lower-most type into said guide, a guard over the remaining type in the channel with which said guide connects and preventing them from being released from the channel and means for operating said kick-off to disengage a type.
13. In a machine for setting type, a longitudinally inclined font having channels in which shouldered type are adapted to be assorted in longitudinal rows, a line unit case, a carrier holding said case in longitudinal position movable across the lower ends of the channels in said font and adapted to bring said case successively into alinement with said rows of type in said channels, said carrier having a longitudinal guide inclining from said font to said case and said carrier, guide and case being adapted to support and suspend said type by their shoulders, means for disengaging a lower-most type in a channel which coincides with said guide to permit said lower-most type passing down said guide and into said case and means for locking said carrier with said guide registering with said channel in said font while said means is operating to disengage a type.
14. In a machine for setting type, a longitudinally inclined font having channels in which shouldered type are adapted to be assorted in longitudinal rows, a line unit case, a carrier holding said case in longitudinal position movable across the lower ends of the channels in said font and adapted to bring said case successively into alinement with said rows of type in said channels, said carrier having a longitudinal guide inclining from said font to said case and said font, guide and case being adapted to support and suspend said type by their shoulders, means for disengaging the lower-most type in a channel which coincides with said guide to permit said type passing down said guide and into said case, a cover over said type in said font, an index on said cover and an index-pointer movable over said index to indicate the character of type with which said line unit case coincides.
15. In a machine for setting type, an inclined font channeled longitudinally to permit assorted shouldered type to hang upon their shoulders, a line unit case having expansible sides, a carriage movably supported to travel across said font and adapted to hold said case and having means for spreading the sides of said case to release the shanks of said type, said carriage having an inclined guide leading down into said case and adapted to receive type from the channels in said font and guide them upon their shoulders down into said case.
16. A type distributor, comprising, in combination, a font for receiving and holding assorted type, a line unit case, a feeder

- movable across said font and adapted to hold said line unit case and to conduct type from said case into said font, means for spreading the sides of said case and means for operating said feeder to release type consecutively from said case into said font. 17. A type distributor, comprising, in combination, a font for holding assorted type, a line unit case, a carrier for said case movable across said font, means for separating the sides of said case and means on said carrier for successively removing type from said case and into said font. 18. A type distributor, comprising, a font for holding assorted type, a line unit case having expansible sides, a carrier movable transversely across said font and with which said line unit case is separably connected, means on said carrier for spreading the sides of said case and holding said case in said carrier and means on said carrier for successively removing type from said case and conducting them into said font. 19. A type distributor, comprising, a font for holding assorted type, a feeder detachably connected to and movable across said font, a line unit case detachably connected to said feeder having sides movable apart and means for removing type from said case and successively placing them in said font and means separating the sides of said case. 20. A type distributor, comprising, in combination, a font for holding assorted type, a type feeder movable across said font and a line unit case carried by said feeder from which type are adapted to be distributed having sides movable apart, said feeder being provided with means for guiding type from said case, means for releasing type successively into said font and means for separating the sides of said case. 21. A type distributor, comprising, in combination, a font for holding assorted type, a type feeder movable across said font and a line unit case carried by said feeder from which type are adapted to be distributed having resilient sides adapted to be sprung apart, said feeder being provided with means for guiding type from said case, means for releasing type successively into said font, means for causing said feeder to be held in engagement with said font while said means for releasing type is being actuated and means for spreading the sides of said case apart. 22. A type feeder inclined longitudinally and having type channels in which type are held in longitudinal rows and adapted to be fed forward by gravity, a line unit case having expansible sides adapted to suspend shouldered type by their shoulders, said feeder having means for spreading the sides of said case and adapted to engage with said font to hold said case longitudinally and to conduct type to be distributed from said case, a kick-off on said feeder adapted to release type successively from said feeder into said font and means for actuating said kick-off. 23. A type distributor, comprising, in combination, an inclined font having longitudinal type channels; a line unit case, a type feeder in which said case is detachably supported, said channels, case and feeder having sides adapted to suspend shouldered type by their shoulders and guide them on their shoulders into said channels, means for releasing type successively from said feeder into said channels and a register co-operating with said font and feeder to align said feeder with a selected channel in said font. 24. In a machine for distributing type, a type font with type channels and aligning depressions, a line unit case, a line unit case carrier, said channels, case and carrier having sides adapted to support and suspend shouldered type by their shoulders, a feeder co-operating with said carrier to release type while supported and suspended by said carrier into said channels and a depressible element on said carrier adapted to seat in said aligning depressions and cause said feeder to coincide with the channels in said font automatically. 25. In a machine for distributing type, a font having type channels, an individual line unit case from which type are adapted to be distributed into said font having expansible sides, a type feeder separably holding said case and movable across the channels in said font having an insert between the sides of said case adapted to spread said sides apart, said feeder having a register adapted to co-operate with said font to register with receiving ends of the channels in said font, a kick-off for releasing a type from said feeder into said font and means for operating said register and kick-off in succession. 26. In a machine for distributing type, a font having a plurality of type channels, a line unit case from which type are adapted to be distributed into the channels of said font having expansible sides, a type feeder movable across the channels in the receiving end of said font and adapted to hold said case and to guide type from said case toward said font, said feeder having means for separating the sides of said case, means for registering said feeder with any of said channels, means for releasing type from said feeder and conducting it into a channel in said font, and means for automatically operating said register and releasing means in succession. 27. In a machine for distributing type, a font having type channels to receive type in assorted groups, a line unit case having separable sides, a type feeder holding said case and movable across the channels in said font, 130

said feeder being adapted to successively align with said channels and to direct type from said case toward said font and having a guide for said type and means for separating the sides of said case, a pin movable in said carrier and adapted to release a type therefrom and permit it to travel into a channel in said font, and means for operating said pin, said line unit case, type guide and the channels in said font being inclined down in the same general direction to permit type to move by gravity from said case into said font.

28. In a machine for distributing type, a longitudinally inclined font having channels holding type in longitudinal rows, a line unit case above the upper end of said font having sides movable apart, a carrier holding said case in longitudinal position movable across the upper ends of the channels in said font and adapted to bring said case into alignment successively with said channels, said carrier having a longitudinally inclined guide adapted to direct type from said case toward one of said channels at a time, means for spreading the sides of said case and said carrier having an opening below the lower-most type in a channel in said font, a kick-off on said carrier adapted to pass through said opening and release said lower-most type from said guide into said font, a hand operating lever adapted to actuate said kick-off and means for automatically returning said lever and kick-off with the latter out of contact with the type in said carrier.

29. In a machine for distributing type, a longitudinally inclined font having channels to hold type in longitudinal rows, a line unit case, a carrier holding said case in longitudinal position, movable across the upper ends of said channels and adapted to bring said case successively into alignment with any of said channels, said carrier having a longitudinal guide inclined from said case toward said font and adapted to direct type from said case toward said font, said carrier having an opening below the lower-most type in said guide, a stop for the series of type at the lower end of said guide, and a kick-off on said carrier adapted to pass through said opening and release the lower-most type in said guide from engagement with said stop, a guard over the remaining type in said guide preventing said remaining type from being released by the action of said kick-off.

30. In a machine for distributing type, a longitudinally inclined font having channels in which shouldered type are adapted to be distributed in longitudinal rows, a line unit case, a carrier holding said case in longitudinal position movable across the upper ends of the channels in said font and adapted to successively align said case with the channels in said font said carrier having a

longitudinal guide inclining from said case toward said font for the type to be distributed from said case, said font, guide and case being adapted to support and suspend said type by their shoulders, a stop at the lower end of said guide for the type, means for lifting the lowermost type in said guide from said stop to permit it to enter a channel in said font, a cover over said type in said font bearing an index to the type in said channels and a pointer movable over said index and supported by said carrier to indicate the character of type which are held in the channels of said font.

31. In a machine for distributing type, a longitudinally inclined font having channels in which shouldered type are adapted to be distributed in longitudinal rows, a line unit case, a carrier holding said case above the upper end of said font and movable across the upper ends of said channels whereby said carrier is adapted to successively register with said channels, said carrier having a longitudinal guide leading from said case toward said font, and said font, guide and case being adapted to support and suspend said type by their shoulders, means for disengaging the lower-most type in said guide whereby said type are adapted to enter said font and means for locking said carrier with said guide registering with any of the channels in said font while said means is operating to disengage a type.

32. A type setter and distributor, comprising, in combination, a flat bed font chambered to receive type in assorted groups, a line unit case having expandible sides, a feeder adjusted to move across said font and holding said case, and a plurality of type adapted to be held in said font or case; said feeder having means for spreading the sides of said case and selecting and removing a type from said font and setting it in said case and for distributing type from said case into said font.

33. A type setter and distributor, comprising, in combination, a flat bed font chambered to receive type in assorted rows, a line unit case having expandible sides, a feeder adjusted to move across the rows of type in said font and adapted in one position to hold said case to receive type and in another position to receive and hold type from said case, said feeder having means for spreading the sides of said case and for successively releasing type from said font and setting them in said case or for releasing type received from said case and distributing them in said font and means for accurately registering said feeder with the proper chambers in said font.

34. A type setter and distributor, comprising, in combination, a flat bed font chambered to receive type in assorted rows, a

line unit case having sides movable apart, a feeder adjusted to move across the rows of type in said font and adapted in one position to hold said case to receive type and in another position to receive and hold type from said case, said feeder having means for separating the sides of said case, a kick-off for successively releasing type from said font and setting them in said case or for releasing type received from said case and distributing them in said font, means for accurately registering said feeder with the proper channels in said font, and means for successively operating said registering means and kick-off.

35. A type setter and distributor, comprising, in combination, a flat bed font longitudinally inclined and channeled to hold rows of assorted type and having means at the lower ends of said channels to prevent normal displacement of type from said font, a type feeder, means for separably attaching said feeder to the upper or lower end of said font to adjust it to any of said channels and a line unit case having separable sides, separably carried by said feeder, said feeder having means for moving the sides of said case apart and being adapted to release type from the lower ends of said channels and set them in said case and to release type received from said case and distribute them into the upper ends of said channels.

36. A type setter and distributor, comprising, in combination, a substantially flat bed font inclined and channeled to hold rows of assorted type, a guide shaft, means for detachably supporting said shaft across the upper or lower end of said font, a line unit

case having separable sides, a feeder adapted to hold said case in position to receive type or to receive and hold type received from said case, said feeder having means for spreading the sides of said case and means for releasing type from the lower end of said font into said case or from said feeder into said font.

37. A type font inclined longitudinally and having channels in which type are held in longitudinal rows and adapted to feed forward by gravity, a line unit case having flexible sides, means for adjusting said line unit case to either the upper or lower end of said font to cause said case to communicate with any of said channels, means for selecting one type at a time for delivery from said font to said case or vice versa and means for bending the sides of said case apart.

38. A type setter and distributor, comprising, in combination, a font for holding type, a line unit case having separable sides and a type feeder movably mounted to travel across said font and adapted to deliver type from said font into said case or to distribute type from said case into said font said feeder being provided with a kick-off for releasing type either from said font or feeder and with means for separating the sides of said case to release type held therein.

In testimony whereof, I have signed my name to this specification, in the presence of two subscribing witnesses.

ERNEST DUSCHER.
